Primary Examiner — Cynthia Ramirez(74) Attorney, Agent, or Firm — Polson Intellectual Property Law, PC; Margaret PolsonCLAIM

The ornamental design for a cart, as shown and described.

DESCRIPTION

FIG. 1 is a front perspective view of a cart showing our new design;

FIG. 2 is a right side elevational view, the left side being a mirror image thereof;

FIG. 3 is a front elevational view thereof;

FIG. 4 is a rear elevational view thereof;

FIG. 5 is a top plan view thereof; and,

FIG. 6 is a bottom plan view thereof.

The features shown in broken lines in the drawing depict environmental subject matter only and form no part of the claimed design.
